UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

SEPARATING PACKAGED GOODS ACCORDING TO WEIGHT DIFFERENCE.

Application filed June 2, 1924. Serial No. 717,304.

To all whom it may concern:

Be it known that I, ALBERT R. THOMPSON, a citizen of the United States, residing at San Jose, in the county of Santa Clara and 5 State of California, have invented certain new and useful Improvements in Separating Packaged Goods According to Weight Difference, of which the following is a specification.

10 My invention relates, in general, to the separating art and, in particular, to the separation of packaged goods according to a difference in weight.

The necessity for such separation may 15 arise from various causes. One of these, perhaps the one of most extended application, is based upon the legal requirement of full measure; and although my invention 20 contemplates the fulfilment of this requirement, irrespective of the nature and form of the packages to be separated, I have in mind particularly its application to the detection 25 of leaky cans from which enough of the contents has escaped to enable their separation 30 from the tight cans because of their diminished weight, and thus to reach the ultimate purpose of setting aside the imperfectly sealed goods.

In the canning art, say, for example, as 35 applied to the processing of milk, the filled cans are passed in continuous line procession through the necessary preheating, cooking and cooling zones at a relatively rapid rate; and it is essential that any method or means 40 for detecting and separating the leaks from the tight cans must necessarily be of such a character as not to interfere with the continuity and speed of the can procession. It is, therefore, one of the objects of my invention to provide for separating the leaks 45 from the tight cans according to their weight difference, while said cans are in motion, and without interrupting the procession being delivered from the processing steps.

45 Another object is to provide simple, effective and accurate means to this end.

With these and other objects in view which will hereinafter appear, my invention 50 consists in the novel apparatus for separating packaged goods according to their weight difference, which I shall now fully describe, it being understood that the device herein disclosed is illustrative, with respect to its specific details, merely of one 55 form especially adapted for canned goods,

and that changes may be made in these details without departing from the spirit of the invention as defined by the claims herein.

In the accompanying drawings—

Fig. 1 is a vertical section of the apparatus on the line 1—1 of Fig. 2. 60

Fig. 2 is a vertical section of the same on the line 2—2 of Fig. 1.

Fig. 3 is a detail elevation of the cam for 65 operating the pick-up fingers.

Fig. 4 is a detail sectional view showing a light can on the depressible or balance platform and the pick-up fingers engaging said can.

Fig. 5 is a detail sectional view showing a 70 heavy can on said platform and the pick-up fingers clearing said can.

1 is a frame in which is mounted a shaft 2 driven by a gear 3, Fig. 2, with which 75 meshes a pinion 4 on the main drive shaft 5, Fig. 1, the shaft and pinion being omitted from Fig. 2 and the gear omitted from Fig. 1.

Keyed to the shaft 2 is the separating 80 member of the machine, which member is here shown as a turret comprising spaced side plates 6 and pocket-plates 7, the latter being secured to the inner or opposing faces of the side plates by the screws 6' shown in Fig. 1. The plates 7 are formed with a peripheral series of outwardly open pockets 7', 85 here shown as four in number, Fig. 1.

Carried by the frame 1, and leading tangentially to the lower descending quadrant of the turret is the inlet or feed member of 90 the machine, here shown as an inclined runway 8 adapted to receive and advance by rolling motion packages of curved cross section, such for example, as cans.

Situated at and in immediate association 95 with the delivery end of the runway 8 and lying below the turret, is the weight selective member of the machine comprising a depressible platform 9 held horizontal by means of arms 10 pivoted at 11, and controlled by an adjustable weight 12, this assembly being that of a common type of balance.

Beyond the platform 9 of the selective 105 member is the discharge member for the heavier packages, said member being here shown as an inclined run-way 13. The delivery end of the feed run-way 8 and the receiving end of the discharge run-way 13 lie at different levels, as seen in Fig. 1, and the 110

movement or stroke of the selective platform 9 is between said levels.

Leading into the upper portion of the turret just below the circular path of the base 5 of the pockets 7' thereof, is the discharge member for the lighter packages, said member being here shown as an inclined runway 14.

Carried by brackets 15, Fig. 2, extending 10 from the outer faces of the turret side-plates 6, are pick-up members 16, here shown as fingers with hook extremities which play into and out of the pockets 7' of the turret plates 7, through openings 6'' in the plates 15 6. Each pick-up finger, as shown in Fig. 2, is yieldably mounted upon a rocking pin 17, its yielding being controlled by a spring 16'; and each rocking pin 17 is controlled in its movement by a spring 17', said movement being effected by means of a crank arm 18, the outer extremity of which carries a roller 19 which travels around a fixed cam 20 mounted in a bushing 1' of the frame 1 concentric with the shaft 2.

25 21, Fig. 2, are stops to limit the outward movement of the pick-up fingers 16.

Associated with the feed-run-way 8 is the overlying feed-control member, consisting of a screw 22, and it will be noted, from Fig. 30 1, that the thread 22' of the screw gradually increases both in height and in width from its outer to its inner end. The screw 22 is supported at its outer end by a frame bracket 23 and at its inner end by the leg 35 24' of a frame bracket 24 which is carried concentrically with the shaft 2, and said screw is rotated by means of a gear 25 keyed on the shaft 2, a pinion 26 meshing with the said gear, a shaft 27 carrying the 40 pinion and journaled at its ends in the frame brackets 23 and 24, and the pinions 28 and 29 on the ends of the shaft 27 and the screw 22 respectively, and the intervening idler 30, all as seen in Fig. 1. By these transmitting 45 connections the feed-controlling screw is driven in predetermined timely relation to the rotation of the turret.

Though the invention is adapted for and 50 is applicable to the separation of packaged goods of varying forms according to their weight differences, said adaptation requiring merely obvious changes without departing essentially from the spirit and scope of the claims hereunto appended, the illustrated 55 form and construction of the device herein disclosed is intended, as heretofore stated, for the separation of packages of curved cross section, such, for example, as product-filled cylindrical cans as shown by 60 31 in Figs. 4 and 5; and, for the sake of simplicity, the operation of said machine will be so described.

The cans in recumbent position and in line procession roll along the feed run-way 65 8 and their advance is controlled by the

screw 22 in such wise that due to the increasing height of the screw thread they are, at first, gradually and without injury engaged thereby, and are increasingly subjected to the supplementary advancing pressure of said thread, and, furthermore, due to the increasing width of said thread, said cans are gradually spaced, in order that as the head of the line reaches the selective platform 9, the individual cans are sufficiently spaced to permit one can only to pass upon, over and from said platform at a time.

70 By a predetermined adjustment of the selective platform 9 the normal position of which is on a level with the delivery end of the feed run-way 8, as seen in Fig. 1, it will remain at this elevation under the weight of the lighter cans, as indicated in Fig. 4; but when the heavier cans are imposed upon it, the platform will be depressed as in Fig. 5, to a level with the discharge run-way 13. The timely rotation of the separating turret with respect to the imposition of the cans upon the selective 75 platform is such that as a can reaches the platform, a pocket 7' of the turret passes down over and partially embraces the can but without supporting it and continues the advance of the can by rolling motion over the platform. At this time the pick-up fingers 16 associated with this pocket are projected into said pocket, as seen in Fig. 2. If the can is light and has not, therefore, depressed the platform 9, said can is held in a position sufficiently elevated to permit the entrance of the fingers 16 into the depressed heads of the can, so that the hooks of said fingers, by engaging the rim of the can heads, as seen in Fig. 4, will, as the turret revolves, pick the can up and lift it from the platform, and carry it bodily to the top of the turret travel. When this upper limit is reached, the fingers 16 are withdrawn, as seen in Fig. 2, and the can is free to be deflected from the pocket 7' into the upper discharge run-way 14 and carried off.

75 But if a can be heavy, it will depress the selective platform 9 and by so doing, the position of the can will be such, as seen in Fig. 5, that the intruding fingers 16 will pass above and clear it, and thus the pocket will simply roll the can off the platform into the lower discharge run-way 13.

80 It will be seen that the detection of the leaky and consequently lighter can and its removal from the can procession take place without interrupting the discharging stream or line, since these effects occur while the cans are moving over the selective platform.

85 The pick-up members are not necessarily hooked fingers, such form being used as best adapted for cans with ends depressed sufficiently to leave a rim for the hooks to en-

gage. The pressure of the finger extremities against the can heads may alone be sufficient to lift the cans, without regard to a rimmed periphery, or positive friction surfaces on said extremities may be used to increase their grip. But where the hook-ends are used, the yielding of the fingers under their spring control will avoid any tendency to injure the can.

10 While, as heretofore stated, my invention is applicable to packaged goods of varying shapes, and especially to packages of curved cross section such as cans of cylindrical section, it is to be noted that this special application results in a peculiar and inherently novel advantage which is due to the shape of the packages, namely their capability of rolling motion the result of their uniformly curved cross section. This rolling motion 15 engendering minimum friction, while imposed upon the weight selective platform, conduces to sensitiveness and accuracy in the operation of the apparatus.

I claim:—

25 1. An apparatus for separating packaged goods according to weight difference, comprising a depressible member adapted to differentially yield under the imposition of the packages; a movable member adapted to engage the packages while upon the depressible member and to remove them therefrom; and supplementary package-engaging devices carried by the movable member for selectively segregating the lighter packages.

30 2. An apparatus for separating packaged goods according to weight difference, comprising a depressible member adapted to differentially yield under the imposition of the packages; a rotatable member adapted to engage the packages while upon the depressible member; means carried by said rotatable member for engaging the packages and moving the heavier ones from said depressible member to one discharge; and other 35 means carried by said rotatable member for engaging and moving the lighter ones to a separate discharge.

35 3. An apparatus for separating packaged goods according to weight difference, comprising a depressible member adapted to differentially yield under the imposition of the packages; a rotatable member having peripheral pockets adapted to embrace the packages while on the depressible member 40 and to move the heavier packages therefrom to one discharge; and pick-up members associated with said pockets for selectively engaging the lighter packages and carrying them to a separate discharge.

45 4. An apparatus for separating packaged goods according to weight difference, comprising a depressible member adapted to differentially yield under the imposition of the packages; a rotatable member having peripheral pockets adapted to embrace the

packages while on the depressible member and to move the heavier packages therefrom to one discharge; pick-up members associated with said pockets for selectively engaging the lighter packages and carrying them to a separate discharge; and means for automatically throwing said pick-up members into and out of action.

5. An apparatus for separating packaged goods according to weight difference comprising a depressible platform balanced to differentially yield under the imposition of the packages; a rotatable turret provided with peripheral pockets adapted to embrace the packages while on the platform and to push the heavier packages therefrom to one discharge; pivotally mounted pick-up fingers carried by the turret and playing into and out of the pockets thereof to engage the lighter packages and carry them to a separate discharge; and means dependent on the turret rotation for automatically swinging said fingers into and out of action.

6. An apparatus for separating packaged goods according to weight difference, comprising a depressible platform balanced to differentially yield under the imposition of the packages; means for feeding the packages successively to and upon said platform while the latter is at its upper level; means for conveying the heavier packages away from the platform when the latter is at its lower level; a rotatable member adapted to engage the packages thereon and to move the heavier ones therefrom when the platform is depressed to its lower level; pick-up members carried by the rotatable member and adapted to engage and carry the lighter packages from the platform when the latter is at its upper level; means for releasing said lighter packages from said pick-up members; and means for conveying said released packages away from the rotatable member.

7. An apparatus for separating packaged goods according to weight difference comprising a depressible member adapted to differentially yield under the imposition of the packages; means for feeding the packages in a continuous stream to and upon said depressible member; a movable member adapted to engage the packages while the latter are moving upon said depressible member and to remove them therefrom; and supplementary package-engaging devices carried by said movable member for selectively segregating the lighter packages.

8. An apparatus for separating packaged goods according to weight difference comprising a depressible member adapted to differentially yield under the imposition of the packages; means for feeding the packages in a continuous stream to and upon said depressible member; a rotatable member adapted to engage the moving packages on said

depressible member, said rotatable member having means for continuing the movement of the heavier packages from said depressible member to one discharge and having other means for selectively engaging and carrying the lighter packages to a separate discharge.

9. An apparatus for separating packaged goods according to weight difference, comprising a depressible platform balanced to differentially yield under the imposition of the packages; a run-way for feeding the packages successively in a moving stream to said platform; means associated with the run-way and acting on the packages to space them, as they approach the platform, sufficiently to admit of but one package being on and moving over the platform at a time; a rotatable member having means for engaging each package on the platform adapted to continue the travel of the heavier ones upon and from said platform to one discharge, and having other can-engaging means adapted to carry the lighter ones to a separate discharge.

10. An apparatus for separating packaged goods according to weight difference, comprising a depressible platform balanced to differentially yield under the imposition of the packages; a run-way for feeding the packages successively in a moving stream to said platform; means associated with the run-way and acting on the packages to space them, as they approach the platform, sufficiently to admit of but one package being on and moving over the platform at a time; a rotatable turret provided with peripheral pockets adapted to embrace the packages upon the platform and to continue the travel of the heavier ones upon and from said platform to one discharge; and pick-up members associated with said pockets adapted to engage and carry the lighter packages to a separate discharge.

11. An apparatus for separating packaged goods according to weight difference, comprising a depressible platform balanced to differentially yield under the imposition of the packages; a run-way for feeding the packages successively in a moving stream to

said platform; a rotatable screw overlying the runway, having a package engaging thread the effective width of which gradually increases towards its discharge end whereby the packages are spaced as they approach the platform to admit of but one package to and moving over the platform at a time; and a rotatable member adapted to engage each package on the platform and to continue the travel of the heavier ones upon and from said platform to one discharge, and to carry the lighter ones to a separate discharge.

12. An apparatus for separating packaged goods according to weight difference, comprising a depressible platform balanced to differentially yield under the imposition of the packages; a run-way for feeding the packages successively in a moving stream to said platform; a rotatable screw overlying the runway, having a package engaging thread the effective width of which gradually increases towards its discharge end whereby the packages are spaced as they approach the platform to admit of but one package to and moving over the platform at a time; and a rotatable turret provided with peripheral pockets adapted to embrace the packages upon the platform and to continue the travel of the heavier ones upon and from said platform to one discharge; and pick-up members associated with said pockets adapted to engage and carry the lighter packages to a separate discharge.

13. An apparatus for separating packaged goods of curved cross section according to weight difference, comprising a weight selective member; means for feeding the goods in continuous traveling procession with rolling movement to and upon said member; means for automatically lifting from said member the rolling lighter goods to one discharge; and means for automatically continuing the rolling of the heavier goods upon and from said member to a separate discharge.

In testimony whereof I have signed my name to this specification.

ALBERT R. THOMPSON.
